DESIGN FOR A TABLE

Wolfgang Hoffmann, Batavia, Ill., assignor to The Howell Company, St. Charles, Ill., a corporation of Illinois

Application August 15, 1936, Serial No. 64,421

Term of patent 3½ years

To all whom it may concern:

Be it known that I, Wolfgang Hoffmann, a citizen of the Republic of Austria, residing at Batavia, in the county of Kane and State of Illinois,
have invented a new, original, and ornamental Design for a Table, of which the following is a specification, reference being had to the accompanying drawing, forming a part thereof.

Figure 1 is a perspective view of a table showing my new design; and

Fig. 2 is an end elevation thereof.

The characteristic feature of the design consists of a table of the type shown having feet that cross at the base with ends projecting at the sides and with a cross bar thereover, substantially as illustrated.

I claim:

The ornamental design for a table, as shown and described.

WOLFGANG HOFFMANN.
